UNITED STATES PATENT OFFICE.

EWALD GOLTSTEIN, OF COLOGNE, GERMANY.

BOTTLE-STOPPER.

No. 926,403.

Specification of Letters Patent.

Patented June 29, 1909.

Application filed July 17, 1903. Serial No. 166,037.

To all whom it may concern:

Be it known that I, EWALD GOLTSTEIN, a subject of the German Emperor, and resident of Cologne, Germany, have invented certain new and useful Improvements in Bottle-Stoppers, of which the following is a specification.

My invention relates to the closing and sealing of receptacles such as bottles and jars, by means of external metallic caps or capsules which are crimped or compressed around the neck of the receptacle and into grooves or beneath shoulders or flanges thereon.

The object of my invention is to provide a capsule which without any separate strengthening device shall be capable of being applied to a receptacle so as to form a closure capable of withstanding high internal pressure and which may yet be readily torn off or removed by the hand alone, without resorting either to weakening the capsule by slits or weakened lines or to the use of separate instruments or tools for opening.

Two specific embodiments of my invention are shown in the accompanying drawings, in which—

Figure 1 is a vertical section of one form of my improved capsule applied to the upper end of a receptacle but not yet in the sealing position; Fig. 2 is a plan view of the capsule; Fig. 3 shows the said capsule on the receptacle in the sealing position; and Fig. 4 is a vertical section showing another form of my invention.

The neck 1 of the receptacle is formed on its outer surface with a bead 2 and a shoulder 3, leaving between them a groove or re-entering portion 4 which has an important function in connection with the capsule 5 as will be explained presently. The capsule is made of a soft sheet metal such as aluminum, thin enough to be readily torn by the hand without being previously weakened and without the use of tools. The top of the capsule presses on a suitable packing such as the ring 6 in Figs. 1 and 3, or the disk 6' in Fig. 4. In the constructions illustrated by the drawings, the top of the capsule is cut through so as to form an integral tongue 7 free at one end and attached to the capsule at the other. This tongue may be lifted by the fingers and pulled downward across the crimping flange for rupturing and removing the capsule after sealing. With this construction, inasmuch as the top of the capsule

has been cut through entirely, it is advisable to interpose a plate 8 between the capsule and the packing, unless the packing is in the form of a disk as in Fig. 4 in which event for certain purposes the plate 8 may be dispensed with. It is important that the depending flange 9 of the capsule should be long enough so that after sealing it will extend below the groove or re-entering portion 4 so as to form a skirt or band which not only increases the frictional resistance of the capsule, but also greatly stiffens it.

In the use of my invention the capsule 5, the plate 8 and the packing 6 or 6' may be first assembled and then applied to the receptacle. Pressure may then be applied for bringing the capsule firmly against the packing (or its covering plate 8) and against the receptacle, into the sealing position illustrated in Fig. 3 (as to one form of my invention). For thus pressing the capsule into sealing position, I prefer to employ apparatus of the character shown in my Letters Patent No. 743,636 dated November 10, 1903. By means of such apparatus, a capsule having the described characteristics may be pressed tightly downward against the receptacle for making an airtight closure and then secured in such position by pressing the depending flange inwardly into locking and frictional engagement with the receptacle. The pressure applied against the flange of the capsule by such an apparatus is very great and forces the soft metal into such tight and intimate contact with the receptacle as to cause it to tightly hug and closely conform with every surface irregularity thereon. The flange is not only pressed into any groove or around and beneath any bead or shoulder purposely formed around the receptacle neck for engagement with the capsule, but is furthermore forced into every little crevice and around every tiny projection or imperfection occurring on the surface of the receptacle. Thus a great number of minute locking engagements are formed between the capsule and the receptacle, many of them almost imperceptible to the naked eye, but in the aggregate sufficient to greatly strengthen the capsule's grip on the receptacle and serving also to materially stiffen the yielding material from which the capsule is formed. Pressing the flange of the capsule under the shoulder 3 and into the groove 4 not only produces a tight locking engagement, but the well-defined circum-

ferential rim or groove which is thus formed in the flange further tends to stiffen the capsule and so increase its efficiency against displacement by internal pressure. The factors which contribute to the wonderful efficiency of my improved capsule, made as it is of a soft readily torn material, and which render unnecessary the use of separate strengthening wires or other holding means, may therefore be summed up briefly as follows: the maximum frictional resistance produced by forcing the flange of the capsule around its entire periphery tightly against the receptacle; the locking engagement of the flange with specially formed grooves or beads on the receptacle; the additional grip which is afforded by forcing the soft metal of the flange into minute locking engagement with every surface imperfection; the stiffening of the capsule resulting from such minute engagements, from the formation of the well defined circumferential rim or groove in the flange of the capsule, and from the presence of the depending skirt or band formed by the flange extending below

the groove or shoulder around the receptacle neck after sealing. It will thus be seen that the soft nature of the material from which the capsule is formed not only facilitates its ready removal, but also performs important functions in strengthening its hold on the receptacle.

I claim as my invention:—

The combination of a receptacle having a reentering portion in its outer surface, and a cap having its top cut through so as to form an integral rupturing tongue for tearing the cap by a downward pull, said cap being also provided with a depending flange in engagement with said reentering portion and formed with a skirt extending below said reentering portion.

In testimony whereof I have affixed my signature, in presence of two witnesses, this sixth day of July, 1903.

EWALD GOLTSTEIN.
